CLOCK

Joseph Palma, Jr., Wheaton, Ill., assignor to Sunbeam Corporation, Chicago, Ill., a corporation of Illinois

Filed Nov. 14, 1960, Ser. No. 62,829

Term of patent 14 years

(Cl. D42—7)

FIG. 1 is a front perspective view of a clock embodying my design;

FIG. 2 is a top plan view thereof;

FIG. 3 is a side elevational view thereof; and

FIG. 4 is a sectional view taken along line 4—4 of FIG. 2.

The essential features of my design reside in portions shown in full lines.

I claim:

The ornamental design for a clock, as shown and described.
